UNITED STATES PATENT OFFICE.

HENRY SPAHLINGER, OF GENEVA, SWITZERLAND.

APPARATUS FOR COLLECTING SERUM.

1,411,068.

Specification of Letters Patent. Patented Mar. 28, 1922.

Application filed February 16, 1918. Serial No. 217,727.

To all whom it may concern:

Be it known that I, HENRY SPAHLINGER, bacteriologist, a citizen of Switzerland, residing at Geneva, Canton of Geneva, in the 5 Confederation of Switzerland, have invented certain new and useful Improvements in Apparatus for Collecting Serum, of which the following is a specification.

Heretofore as far as I am aware, it has 10 been customary in extracting serum, to permit the blood from which the serum is to be extracted, to coagulate to a predetermined extent, and then to apply pressure to the same in order to cause the serum to ooze 15 from the coagulated blood. In this process, the amount of the weight employed, depends upon the solidity of the coagulated clot of blood, and the quantity of serum obtained depends relatively upon the amount of 20 compression and the time during which the blood is compressed; the blood being more or less fluid, as will be understood, has heretofore limited the compression to which it could be subjected, and this in turn, has limited 25 the quantity of serum obtained. Now I have discovered that by employing devices by which the blood from which the serum is to be extracted is suitably penetrated, the coagulation of the blood is materially augmented 30 and consequently its solidity is greatly increased. This of course permits of the application of greater weight which in a given time results in an increased yield of the serum. In carrying out this invention, therefore, I employ a suitable receptacle made of glass or other suitable material and fitted with a plunger plate extending 35 from which are series of projections adapted to penetrate the clot of blood from 40 which the serum is to be extracted, in order to augment the coagulation of the blood to increase its solidity, thereby making it possible to compress it to a greater extent with a consequent increase in the yield of serum 45 obtained.

In carrying out the invention, the receptacle is preferably provided with a removable cap or cover through which the plunger rod passes, the same being provided at its 50 outer end with a plate or table upon which the weights employed may be placed; and the invention also includes a suitable joint between the plunger rod and that portion of the cap or cover through which the same 55 passes in order to ensure the sterility of this part of the apparatus. Furthermore, in in-

troducing the blood to the receptacle, I prefer to employ a curved intake pipe, with the orifice at its inner end adjacent or in close proximity to the inner surface of one 60 of the walls of the receptacle, and provided at its outer end with overhanging portions, so that the blood as admitted to the receptacle, will flow down the inner surface of this wall of the receptacle without frothing, 65 and in being admitted, will not carry along with it extraneous matter, which if uncovered, might enter the intake orifice of this pipe or tube.

In the drawing:

Fig. 1 is a central longitudinal section of the apparatus comprising my present invention.

Fig. 2 is a plan view of the cover.

Fig. 3 is an inverted plan view of the 75 metal plate employed as a press, and

Fig. 4 is a central view showing a modified form of this plate.

Referring to the drawing *a* indicates a cylindrical glass receptacle, *b* a cover of 80 metal provided with a rim *b'*. The cover *b* is made with a central stem or sleeve *c* provided with the screw *d*. In the cover there is an opening *e* fitted with a small metal pipe *f* curved into semicircular form for the 85 introduction of blood into the receptacle. The pipe *f* is cut at its upper end in the form of a beak so that the top extends over the orifice and makes a protective extension *g* designed to prevent germs from the air 90 from falling into the pipe and getting into the receptacle in the course of the operation of taking blood and passing the same to the receptacle. The orifice at the lower end *h* of this pipe is placed a few millimetres from the inner wall of the receptacle. The cover 95 *b* is also perforated as indicated at *i* forming an opening for introducing into the receiver a small glass pipe used for the removal of the serum.

The apparatus for compressing and penetrating the clot of blood consists of a metal plate *l* provided with the teeth *m* and a rod *k*. The plate is provided with series of perforations *n*, placed between the teeth *m* and 105 serving in the use of the apparatus to promote the oozing of the serum up to the top of the plate. As indicated in Fig. 4, blades *m'* may be employed for the purpose of penetrating the clot of blood instead of the teeth 110 as shown in Fig. 3. The outer end of the rod *k* is fitted with a metal disc *o* provided

with a groove *p* to which is fixed the upper part of a rubber tube *r*, the lower end of the rubber tube being attached to the upper part *c'* of the sleeve *c*, and the object of which is to ensure sterility of the apparatus during the operation of raising and lowering of the plate *l*. Above the metal disc *o* and forming part thereof is an extension *g* which serves as a support for a plate *s*, which screws onto the extension *g*, and upon which plate weights may be placed during the use of the apparatus, to provide the necessary pressure to produce a desired yield of serum.

In the operation of the apparatus, the various parts are first carefully washed, and then the cover *b* is placed upon the rod *k* by causing this latter to pass through the sleeve *c*. The metal disk *o* is then screwed onto the end of the rod *k* and the rod fixed in the sleeve *c* by the screw *d*. The cover *b* is now placed upon the receiver *a*, and the space *u* (see Figure 1) which may exist between the rim *b'* of the cover and the outer wall of the receiver is carefully stuffed with cotton. The rubber tube *r* is then attached at *p* and *c'* and the openings *g* and *i* are plugged with cotton stoppers (not shown in the drawing), and the sterilization of the apparatus is proceeded with. When this is complete the blood from which it is desired to collect the serum is introduced into the apparatus. To effect this introduction sanitarily the cotton stopper in the opening *g* is removed and is replaced by a glass cannula which is connected to the trocar by a suitable tube.

In this operation of taking the blood, the plate *l* is preferably first secured in the desired position, and a quantity of blood admitted to the receptacle, sufficient to rise therein around the teeth ends or blades *m'* to a level adjacent the under surface of the plate, but not so as to come into contact with the plate.

In flowing into the receptacle, due to the close proximity of the inner orifice of the tube *f*, the blood is projected against the wall of the receptacle and runs down the same so as to prevent the formation of froth; the coagulation of the blood is then permitted to take place for a predetermined time, and as will be apparent, by the projections penetrating the clot of blood or the upper portions thereof, the coagulation of the penetrated portion of the clot of blood will be materially augmented and its solidity greatly increased. The plate *l* is then released by unscrewing the set screw *d* and suitable weights placed upon the plate *s* to compress the clot of blood. It will be apparent that by the increased degree of coagulation and consequent solidity, greater or heavier weights may be placed on the plate *s* and consequently an increased yield obtained, than could possibly be the case if

the coagulation of the blood were not augmented by the use of projections extending from the presser plate *l*.

After two or three days the serum which has oozed through the holes *n* in the plate *l* is removed, care being taken to first singe the opening *i*. The cotton stopper placed in the opening *i* as has been described previously, is removed and quickly replaced by a pad of sterilized cotton under the protection of which the small pipe for removing the serum is introduced into the receptacle *a* through the hole *i*. The serum having been collected, the small pipe is slowly withdrawn, care being taken not to displace the pad of cotton which closes the opening *i* which pad serves to close the opening *i* and prevent any germs from falling into the receptacle. After having stirred up the clot the pressure may be increased by additional weights and after a period of from 24 to 48 hours another quantity of serum may be obtained under the same conditions.

I claim as my invention:

1. In an apparatus for extracting serum, a receptacle for holding blood from which the serum is to be extracted, and a device within the receptacle adapted to extend into the blood therein to augment its coagulation and increase the solidity thereof. 90

2. In an apparatus for extracting serum, a receptacle for holding blood from which the serum is to be extracted, a device within the receptacle adapted to extend into the blood to augment its coagulation and increase the solidity thereof, and means connected to the said device and extending through the walls of the receptacle for operating the said device exteriorly of the receptacle. 100

3. In an apparatus for extracting serum, a receptacle for holding blood from which the serum is to be extracted, a device within the receptacle adapted to extend into the blood to augment its coagulation and increase the solidity thereof, means connected to the said device and extending through the walls of the receptacle for operating the said device exteriorly of the receptacle, and means associated with the aforesaid means to insure the sterility of that part of the same which enters the receptacle. 110

4. In an apparatus for extracting serum, a receptacle for holding blood from which the serum is to be extracted, a plate adjustable to position within the receptacle, and devices extending from the said plate and adapted to be surrounded by the blood in the receptacle to augment its coagulation and increase the solidity thereof. 120

5. In an apparatus for extracting serum, a receptacle for holding blood from which the serum is to be extracted, a plate movable within the receptacle, projections connected to the said plate and extending therefrom 130

so as to extend into the blood in the receptacle to augment its coagulation and increase the solidity thereof, and a rod connected to the said plate and extending 5 through a wall of the receptacle for adjusting the plate to position within the receptacle.

6. In an apparatus for extracting serum, a receptacle for holding blood from which the 10 serum is to be extracted, a plate movable within the receptacle, projections connected to the said plate and extending therefrom so as to extend into the blood in the receptacle to augment its coagulation and increase the solidity thereof, a rod connected 15 to the said plate and extending through a wall of the receptacle for adjusting the plate to position within the receptacle, and means associated with the rod for insuring 20 the sterility of that portion thereof which is permitted to enter the receptacle.

7. In an apparatus for extracting serum, a receptacle, a cover therefor, a rod passing through the said cover, a plate secured to 25 that end of the rod which extends into the receptacle, and a flexible covering for the joint between the rod and the cover of the receptacle to ensure the sterility of that part of the rod which is permitted to enter 30 the receptacle.

8. In an apparatus for extracting serum, a receptacle, a cover therefor, a rod passing through a bearing provided therefor in the said cover, a plate secured to that end of 35 the rod which lies within the receptacle, and a tube of flexible material secured at one end to the said bearing for the rod and at the other end to the outer portion of the said rod to ensure the sterility of that part 40 of the rod which enters the receptacle.

9. In an apparatus for extracting serum, a receptacle, a cover therefor, a rod passing through a bearing provided therefor in the said cover, a plate secured to that end of 45 the rod which lies within the receptacle, a disk secured to the said rod adjacent the

outer end, and a rubber tube through which the said rod passes, and which at one end is secured to the said bearing in the cover and at the other end to the said disk on the 50 said rod to ensure the sterility of that part of the rod which enters the receptacle.

10. In an apparatus for extracting serum, a receptacle, an intake tube for the blood from which the serum is to be extracted, 55 the intake tube being secured in the receptacle with its discharge orifice within the receptacle adjacent the surface of one wall thereof and with its intake orifice exterior of the receptacle and covered by an overhanging part thereof to prevent germs from falling into the said inlet tube.

11. In an apparatus for extracting serum, a substantially semi-circular intake pipe for the blood from which the serum is to be 65 extracted, the said intake being so connected to the receptacle that its discharge orifice lies within the receptacle adjacent the surface of one wall thereof and its intake 70 orifice exterior of the receptacle and covered by an overhanging part thereof to prevent germs from falling into the said intake pipe.

12. In an apparatus for extracting serum, a receptacle, a cover therefor and a substantially semi-circular intake pipe for the blood 75 from which the serum is to be extracted, the said intake pipe extending through and being secured in the said cover in such a position that when the cover is in place, the discharge orifice of the intake pipe lies adjacent the face of one of the walls of the receptacle and the intake orifice thereof exterior of the receptacle and covered by an overhanging part thereof to prevent germs 80 from falling into the said intake pipe. 85

In testimony whereof I have affixed my signature in presence of two witnesses.

HENRY SPAHLINGER.
